UNITED STATES PATENT OFFICE.

VYVYAN C. BENNETT AND GREY DRUMMOND, OF EL ORO, MEXICO.

PULP-DISTRIBUTING MACHINE.

1,100,649.

Specification of Letters Patent. Patented June 16, 1914.

Application filed April 5, 1913. Serial No. 759,201.

To all whom it may concern:

Be it known that we, VYVYAN C. BENNETT and GREY DRUMMOND, both subjects of the King of Great Britain, residing at El Oro, 5 Estado de Mexico, Republic of Mexico, have invented certain new and useful Improvements in Pulp-Distributing Machines, of which the following is a specification.

This invention relates to improvements in 10 machines for distributing ore pulp to ore dressing machines, such, for instance, as tube mills. The improved machine is especially intended to supply a gang or series of ore dressing machines, and its object is 15 to simultaneously deliver to any particular number of machines up to a certain point, streams of pulp of uniform character, consistency, and volume, and it is especially capable of effecting equal, or substantially 20 equal, divisions of the pulp for either all of the machines of the gang or series, or for a number of said machines less than the total number thereof in the gang or series. That is to say, assuming, for the sake of 25 example, that there are six ore dressing machines to which the pulp is to be distributed: the machine which forms the subject matter of the present invention is adapted to deliver uniform and equal streams of pulp to 30 all of the six dressing machines, or to any five, or four, or less number of such dressing machines.

It will, of course, be understood that the 35 amount of pulp supplied by the feed launder or feed pipe is not affected by the number of dressing machines to which the pulp is to be distributed, and consequently, that the streams of pulp passing to said dressing machines, while uniform in character and 40 volume with one another, will be of greater volume in the case of a smaller number of dressing machines to be supplied than they will in the case of a larger number of such machines.

45 The invention includes means for conveniently and quickly effecting the interchangeable application of the machine to different particular numbers of dressing machines at different times.

50 The essential features of the invention are a collecting pan or equivalent provided with a certain number of compartments, a dividing pan or equivalent which receives the pulp from the collecting pan and in which

the streams to supply the different dressing 55 machines are formed, a distributing element which receives the pulp from the battery launder and by which the pulp is passed to the collecting pan, and a number of distributing spouts or connections leading from 60 the several chambers of the collecting pan and mounted so as to be put into communication with any desired chamber of the distributing pan. Under ideal conditions, the 65 number of chambers in the collecting pan is a multiple of the number of chambers in the dividing pan, and the discharge spouts or connections from the collecting pan are so arranged that equal numbers thereof communicate with the several chambers of the 70 dividing pan, or with a selected number of the chambers of the dividing pan.

An embodiment of the invention is illustrated in the accompanying drawings, 75 wherein:

Figure 1 is a vertical central sectional view of a machine in which the features of improvement are incorporated; Fig. 2 is a plan view thereof; Fig. 3 is a plan view of the dividing pan. This figure shows dia- 80 grammatically and by dotted lines the relation of the discharge spouts from the collecting pan, and of the tubes which lead from the several chambers of the dividing pan to the ore dressing machines. Fig. 4 is 85 a detail perspective view of the distributing element.

Similar characters of reference designate 90 corresponding parts throughout the several views.

The working parts are supported by a frame work of any suitable construction, and consist essentially of the distributing element 1, the stationary collecting pan 2, the dividing pan 3, and the discharge spouts 95 or connections 4 by which the pulp is transferred from the pan 2 to the pan 3.

In the embodiment shown, the element 1 is mounted for rotation and is in the form of a snail channel. The channel 1 is carried by a pendant shaft 5 which is revolved by the reaction of the pulp stream or by any suitable means and is arranged in relation to a feed launder or feed pipe 6 and to the chambers or compartments 7 of the pan 2. 100 The launder 6 discharges the pulp in a zone concentric to the axis of rotation of the channel 1 and the pulp uniformly discharges 105

from the open end of said channel into the successive compartments 7, consequent to the rotation of the channel relatively to said compartments. To facilitate the discharge 5 of pulp from the chambers or compartments 7, each compartment has an inclined bottom communicating at its lowest point with a discharge duct 8, and the spouts 4, which are of somewhat ogee form, and terminate at 10 points above the pan 3 are in communication with the several discharge ducts 8 and are connected to the base plate of the pan 2, preferably through the agency of swivel joints 9.

15 The office of the chamber 3 is to divide the pulp into a number of streams of uniform consistency and volume, corresponding to the number of dressing machines to which the pulp is to be delivered. For this purpose, the chamber 3 is divided into a number 20 of compartments 10, which are preferably of annular form and are concentrically related, each compartment 10 preferably having a bottom lining made up of a mixture of concrete and silex and faced with 25 cement. Each compartment 10 is connected by a discharge pipe 11 to a particular dressing machine of the group to be supplied. The bottoms of the compartments 10 are inclined, and the tubes 11, of course, lead from 30 the lowest point of said bottoms.

In the embodiment shown, the chamber 2 has twenty-eight compartments 7, and the chamber 3 has seven compartments 10. 35 In such event, it will be understood that the maximum number of dressing machines constituting the group to be supplied will be seven. It is also assumed that all of the dressing machines are to be supplied with 40 pulp, in which case the spouts 4 are so arranged that four of them discharge into each compartment 10, (Fig. 3). It will be obvious that the spouts 4 and the chamber 3 thus coact to produce seven streams of pulp 45 of uniform character and volume which are passed by the several pipes 11 and the several dressing machines. If, for any reason, all of the dressing machines are not all to be used, but a number less than the total 50 number are to be supplied, the spouts 4 are adjusted relatively to the compartments 10 of the chamber 3 to effect a division of the aggregate mass of pulp into equal or substantially equal streams, corresponding in 55 number to the number of dressing machines to be supplied. In some cases it may not always be possible to have a theoretical equality of the streams, but in any event, the streams will be substantially equal. To 60 obtain an absolute equality of the streams under all conditions, the number of compartments in the chamber 2 should be the least common multiple of all the numbers of compartments which can be selected from

the chamber 3. To illustrate: Assuming 65 that there are four dressing machines and that the chamber 3 has but four compartments 10, the chamber 2 will have twelve compartments 7, since twelve is the least common multiple of the factors 1, 2, 3, and 70 4. But when the number of dressing machines and the number of compartments in the chamber 3 is over 4, it is not feasible to have absolute equality of all the streams, because the member which is the least common multiple of the several factors which 75 can be produced from the number of compartments in the chamber 3 will be such that a corresponding number of compartments 7 in the chamber 2 would be impractical, because it would render the machine too cumbersome. Thus, if it be assumed that there 80 are five compartments 10 in the chamber 3, the least common multiple of the numbers 1, 2, 3, 4, and 5 is 60, but the use of 60 compartments 7, suitable for the purposes in view, would be impractical, for the reasons stated. As a matter of fact, it is impractical 85 to have more than about thirty-five compartments 7, and such a number of compartments 7 will be sufficient to enable the production of substantially equal streams within the numerical limits of the average 90 group or gang of dressing machines.

Under normal conditions, it is important 95 that the supply of pulp to the machines should be uniform, and as fully explained above, the principal object of the invention is to secure this uniformity. It may sometimes happen, however, that it is desirable 100 to supply a greater or less amount of pulp to some one machine of the group than to the others. Thus, in the case of tube mill machines, it may happen, for one reason or another, that one machine is not working 105 efficiently, for example, owing to its not having its requisite load of grinding pebbles. In such a case, it might be deemed advantageous to deliver a stream having less volume to this machine than the streams delivered to the other machines. This result is 110 achieved by such an arrangement of the spouts or connections 4 as will make the particular stream to be delivered to the machine not having its requisite load of grinding 115 pebbles of less volume than the other streams, and to make these other streams uniform in volume with one another, or as nearly uniform as possible under the circumstances. Thus, in the case assumed by the 120 drawings, where seven machines are to be supplied, and under ideal conditions, each stream will be made up of the product delivered by four of the spouts 4; in the event that one of the dressing machines, for any 125 reason, does not have the capacity for a stream corresponding to the product of four spouts 4, the channel 10 which supplies this

particular dressing machine may, of course, receive the product of but three of the spouts 4, in which case the odd spout will be turned to communicate with some other channel, 5 preferably the channel of the machine which, if there is any distinction in capacity, as to the remaining machines of the group, has the greatest capacity.

The improved machine is also useful in 10 that one of the spouts 4 may without interference with the normal operation of the machine be turned to deliver a stream into the sample boxes, and in this way an accurate sample may be obtained. By noting the 15 time element in taking the sample, a close estimate of the quantity of the material flowing through the plant may be made.

Having fully described our invention, we claim:

20 1. In a pulp distributing machine, a stationary collecting chamber having compartments therein provided with inclined bottoms, a stationary dividing chamber having compartments therein provided with inclined bottoms, discharge pipes leading from the compartments of the dividing chamber at the lowest point of the inclined bottoms thereof, a discharge spout for each compartment of the collecting chamber leading from the lowest point of its inclined bottom, each discharge spout being adjustable whereby it may establish direct and continuous communication between the collecting chamber compartment from which it leads and any 30 selected compartment of the dividing chamber, and in the normal operation of the machine terminating at a point above the dividing chamber, the number of compartments in the collecting chamber being such relatively to the number of compartments in the dividing chamber that a plurality of groups of said spouts, each group composed of a plurality of spouts, may simultaneously communicate with all or any selected number of the respective compartments of the dividing chamber, and means for distributing the pulp uniformly to all the compartments of the collecting chamber.

2. In a pulp distributing machine, a stationary collecting chamber having compartments therein provided with inclined bottoms, a stationary dividing chamber having compartments therein provided with inclined bottoms, discharge pipes leading from the compartments of the dividing chamber at the lowest point of the inclined bottoms thereof, a discharge spout for each compartment of the collecting chamber leading from the lowest point of its inclined bottom, each discharge spout being adjustable whereby it may establish direct and continuous communication between the collecting chamber compartment from which it leads and any selected compartment of the dividing

chamber, and in the normal operation of the 65 machine terminating at a point above the dividing chamber, the number of compartments in the collecting chamber being such relatively to the number of compartments in the dividing chamber that a plurality of 70 groups of said spouts, each group composed of a plurality of spouts, may simultaneously communicate with all or any selected number of the respective compartments of the dividing chamber, a rotatable snail channel 75 arranged above the collecting chamber, and a feed launder discharging into the snail channel, the latter serving to discharge the pulp uniformly to the compartments of the collecting chamber.

3. In a pulp distributing machine, a stationary collecting chamber having an inclined bottom, a stationary dividing chamber having compartments therein provided with inclined bottoms, discharge pipes leading from the compartments of the dividing chamber at the lowest point of the inclined bottoms thereof, a plurality of equi-distant discharge spouts leading from the lowest point of the inclined bottom of the collecting chamber, 80 each discharge spout being adjustable whereby it may establish direct and continuous communication between the collecting chamber and any selected compartment of the dividing chamber, and in the normal operation of the machine terminating at a point above the dividing chamber, the number of discharge spouts being such relatively to the 85 number of compartments in the dividing chamber that a plurality of groups of said spouts, each group composed of a plurality of spouts, may simultaneously communicate with all or any selected number of the respective compartments of the dividing chamber, and means for distributing the pulp 90 uniformly throughout the extent of the collecting chamber.

4. In a pulp distributing machine, a stationary collecting chamber having compartments therein, a stationary dividing chamber having compartments therein, discharge pipes leading from the compartments of the dividing chamber, an angularly disposed discharge spout swiveled to the base of each compartment of the collecting chamber, each discharge spout being adjustable whereby it may establish direct and continuous communication between the collecting chamber compartment from which it leads and any selected compartment of the dividing chamber, 110 and in the normal operation of the machine terminating at a point above the dividing chamber, the number of compartments in the collecting chamber being such relatively to the number of compartments in the dividing chamber that a plurality of groups of said spouts, each group composed of a plurality of spouts, may simultaneously communicate

with all or any selected number of the respective compartments of the dividing chamber, and means for distributing the pulp uniformly to the compartments of the collecting chamber.

5. In a pulp distributing machine, a stationary collecting chamber having compartments therein, a stationary dividing chamber having compartments therein, discharge pipes leading from the compartments of the dividing chamber, an angularly disposed discharge spout swiveled to the base of each compartment of the collecting chamber, each discharge spout being adjustable whereby it 10 may establish direct and continuous communication between the collecting chamber compartment from which it leads and any selected compartment of the dividing chamber, and in the normal operation of the machine terminating at a point above the dividing chamber, the number of compartments in the collecting chamber being such relatively to the number of compartments in the dividing chamber that a plurality of 15 groups of said spouts, each group composed of a plurality of spouts, may simultaneously communicate with all or any selected number of the respective compartments of the dividing chamber, a rotatable snail channel arranged above the collecting chamber, and a feed launder discharging into the snail channel, the latter serving to discharge the pulp uniformly to the compartments of the collecting chamber.
- 20 6. In a pulp distributing machine, a stationary collecting chamber having compartments therein, a dividing chamber having compartments therein, discharge pipes leading from the compartments of the dividing chamber, a discharge spout for each compartment of the collecting chamber, each discharge spout being adjustable whereby it may establish direct and continuous communication between the collecting chamber compartment from which it leads and any selected compartment of the dividing chamber, and in the normal operation of the machine terminating at a point above the dividing chamber, the number of compartments in the collecting chamber being such relatively to the number of compartments in the dividing chamber that a plurality of groups of said spouts, each group composed of a plurality of spouts, may simultaneously communicate with all or any selected number of the respective compartments of the dividing chamber, a rotatable snail channel arranged above the collecting chamber, and a feed launder discharging into the snail channel, the latter serving to discharge the pulp uniformly throughout the extent of the collecting chamber.
- 25 7. In a pulp distributing machine, a stationary collecting chamber, a dividing chamber having compartments therein, discharge pipes leading from the compartments of the dividing chamber, a plurality of equi-distant discharge spouts leading from the collecting chamber, each discharge spout being angularly disposed, swiveled to the base of the collecting chamber, in the normal operation of the machine terminating above the dividing chamber, and having such angularity that it may be adjusted to establish direct and continuous communication between the collecting chamber and any selected compartment of the dividing chamber, or to deliver a stream of pulp at a point outside of the dividing chamber, the number of discharge spouts being such relatively to the number of compartments in the divid-

65 tant discharge spouts leading from the collecting chamber, each discharge spout being adjustable whereby it may establish direct and continuous communication between the collecting chamber and any selected compartment of the dividing chamber, and in 70 the normal operation of the machine terminating at a point above the dividing chamber, the number of discharge spouts being such relatively to the number of compartments in the dividing chamber that a plurality of groups of said spouts, each group composed of a plurality of spouts, may simultaneously communicate with all or any selected number of the respective compartments of the dividing chamber, and means 75 for distributing the pulp uniformly throughout the extent of the collecting chamber.

8. In a pulp distributing machine, a stationary collecting chamber, a dividing chamber 85 having compartments therein, discharge pipes leading from the compartments of the dividing chamber, a plurality of equi-distant discharge spouts leading from the collecting chamber, each discharge spout being 90 adjustable whereby it may establish direct and continuous communication between the collecting chamber and any selected compartment of the dividing chamber, and in the normal operation of the machine terminating at a point above the dividing chamber, the number of discharge spouts being such relatively to the number of compartments in the dividing chamber that a plurality of groups of said spouts, each group composed of a plurality of spouts, may simultaneously communicate with all or any selected number of the respective compartments of the dividing chamber, a rotatable snail channel arranged above the collecting chamber, and a feed launder discharging into the snail channel, the latter serving to discharge the pulp uniformly throughout the extent of the collecting chamber.

9. In a pulp distributing machine, a stationary collecting chamber, a stationary dividing chamber having compartments therein; discharge pipes leading from the compartments of the dividing chamber, a plurality of equi-distant discharge spouts leading 100 from the collecting chamber, each discharge spout being angularly disposed, swiveled to the base of the collecting chamber, in the normal operation of the machine terminating above the dividing chamber, and having such angularity that it may be adjusted to establish direct and continuous communication between the collecting chamber and any selected compartment of the dividing chamber, or to deliver a stream of pulp at a point outside of the dividing chamber, the number of discharge spouts being such relatively to the number of compartments in the divid-

ing chamber that a plurality of groups of said spouts, each group composed of a plurality of spouts, may simultaneously communicate with all or any number of the respective compartments of the dividing chamber, and means for distributing the pulp uniformly throughout the extent of the collecting chamber.

In testimony whereof we have hereunto set our hands in presence of two subscribing 10 witnesses.
